UNITED STATES PATENT OFFICE

JOHN A. WILLIAMS, OF NEW YORK, N. Y., ASSIGNOR TO THOMAS ADAMS, JR.,
OF SAME PLACE.

SELF-LIGHTING GAS-BURNER.

SPECIFICATION forming part of Letters Patent No. 627,631, dated June 27, 1899.

Application filed November 26, 1897. Renewed May 26, 1899. Serial No. 718,426. (No model.)

To all whom it may concern:

Be it known that I, JOHN A. WILLIAMS, a citizen of the United States, residing at New York, (Brooklyn,) in the county of Kings and 5 State of New York, have invented certain new and useful Improvements in Self-Lighting Gas-Burners, of which the following is a specification.

My present invention relates to improvements in automatic lighting devices for gas-jets, the construction and advantages of which will be hereinafter set forth, reference being had to the annexed drawings, in which—

Figure 1 is a perspective view of the device, 5 the parts being shown in the relation which they occupy when the flame is not burning; Fig. 2, a similar view showing the parts in their relative positions when the gas is lighted and Fig. 3 a top plan view.

○ The object of my invention is to provide a simple and efficient automatic igniting device for gas-jets, and the forms shown are illustrative of an embodiment of my invention broadly claimed in application Serial No. 5 659,872.

In the drawings, A indicates the burner, to which is attached, just below the tip, a thermostatic coil B. The coil comprises two strips of metal having different coefficients of expansion so united that as the coil is heated it will unwind. As shown, the coil occupies a horizontal position or is in a plane at right angles to the axis of the burner. The outer or free end of the coil is bent at right angles, 5 forming a shoulder or abutment C, and from this point an arm D extends upward in line with the opening in the tube when the parts are in the relation shown in Fig. 1. Secured to the upper end of this arm is a basket E, containing platinum-black or other substance possessing the power of absorbing or condensing oxygen and causing the gas to ignite when it comes in contact therewith. Instead of the basket any other suitable means may be employed to bring about the desired result.

To one side of the burner, in line with the opening in the tube, I provide a stop F, which extends out in the path of the coil and, coming in contact with the end thereof, holds the

arm D in alinement with the tip, and consequently insures the gas coming in contact with the basket as it issues from the burner. A similar stop G is provided at a point ninety degrees from the stop F, so that when the gas is ignited and the coil expands the shoulder 55 C will come in contact with the stop G and prevent further movement of the coil. The relation of the parts is shown in Fig. 2, and it will be noted that the basket stands to the flat side of the flame and out of contact therewith, so that the igniting material will not become deteriorated by direct contact with the flame. The stops F and G always insure the parts being held in their proper position.

The operation of the device will be readily 65 understood. When the gas is turned on, it will come into direct contact with the basket and the igniting material contained therein and will immediately be ignited. So soon as this occurs the heat generated by the flame 70 will act upon the thermostatic coil and cause it to expand, carrying the arm D and the basket E around until the shoulder C comes in contact with the stop G, in which position the coil will be held until the gas is turned 75 off. Immediately the gas is turned off the coil begins to cool, and the basket or igniting device E will return to its former position, as indicated in Fig. 1, ready to again ignite the gas as it issues from the jet.

Having thus fully described my invention, what I claim is—

1. In combination with a gas-burner, a thermostatic coil connected thereto and encircling the same at its upper end, and an igniting 85 substance carried by the free end of the coil in line with the opening in the burner.

2. In combination with a gas-burner, a thermostatic coil connected thereto and encircling the same at or near its upper end, an igniting 90 substance carried by the free end of the coil, and stops to limit the movement of the coil, substantially as and for the purpose described.

3. In combination with a gas-burner, a thermostatic coil connected thereto and encircling the same at or near its upper end, an igniting 95 substance carried by the free end of said coil,

a stop in line with the opening in the burner, and a second stop placed at approximately ninety degrees to the first stop.

4. In combination with a gas-burner, a thermostatic coil B connected thereto and encircling the same at or near its upper end, a shoulder C formed at the outer end of said coil, arm D, igniting substance E carried by the upper end of said arm, and stops F and G connected to the burner, substantially as and for the purpose described.

5. In combination with a gas-burner, a thermostatic coil lying in a horizontal plane around the upper end of the burner, and an igniting substance carried by the outer end of the coil normally in line with the opening in the burner, whereby when the gas is turned

on it will ignite and the coil be caused to expand and the igniting substance withdrawn from the flame, substantially as described. 20

6. In combination with a gas-burner; a thermostatic coil surrounding the same and connected thereto at one end; and a substance capable of igniting the gas by coming into contact therewith, carried by the free end of 25 the coil in line with the flame, substantially as described.

In witness whereof I hereunto set my hand in the presence of two witnesses.

JOHN A. WILLIAMS.
